UNITED STATES PATENT OFFICE.

LOTHAR R. ZIFFERER, OF SAN FRANCISCO, CALIFORNIA.

ANCHOR-LOCK FOR BUILDING STRUCTURES.

943,906.

Specification of Letters Patent. Patented Dec. 21, 1909.

Application filed December 26, 1907. Serial No. 407,991.

To all whom it may concern:

Be it known that I, LOTHAR R. ZIFFERER, citizen of the United States, residing in the city and county of San Francisco and State of California, have invented new and useful Improvements in Anchor-Locks for Building Structures, of which the following is a specification.

My invention relates to a locking device for the attachment of fixtures to concrete or other walls of buildings.

It consists in the combination of parts, and in details of construction which will be more fully explained by reference to the accompanying drawings, in which—

Figure 1 is a view showing a section of wall or ceiling, with my attachment in position and ready to expand. Fig. 2 is a sectional view of the same expanded and locked. Fig. 3 is an end view. Fig. 4 is a perspective view of one of the half members of the segment. Fig. 5 is a side sectional view of the same. Fig. 6 is a transverse section taken through the line $x-x$ of Fig. 4. Fig. 7 is a similar section on the line $y-y$ of Fig. 4. Fig. 8 shows the nut in position at the inner end of the half shell. Fig. 9 shows the nut when drawn to the outer end of the shell.

It is the object of my invention to provide a means for locking fixtures of any description firmly into a brick, concrete, or other wall made of a material which is liable to crumble and allow fixtures to become loosened.

As shown in the present drawings, A—A are two segments which when placed together form a complete shell, the segments meeting on the line 2. These segments have the interior made hollow, and the inner end has a hole 7 of such size as to receive and guide a bolt 3 which may be an ordinary standard bolt.

The interior of the shell sections are made of such form as to receive a hexagonal nut 6, and allow it to be advanced upon the screw-bolt 3 without turning within the shell. In order to expand the shells and cause them to lock within the hole, the interior sides 4 which form the opposing bottom of the shells, are made to converge from the inner to the outer end, as shown in Figs. 1 and 2, and the corresponding sides of the nut, sliding upon these surfaces, when the nut is advanced by turning the bolt, will

cause the shells to separate from each other, and their exterior surfaces to bind in the hole in which the device is placed. Upon these exterior surfaces, and in line with the inclined surfaces 4, are formed teeth 60 or serrations 5. These teeth have a broad base where they unite with the surfaces of the shell segments, and taper to a point when viewed transversely; this structure serving as a reinforce to strengthen the 65 shells at the angles of the surfaces 4. The serrations are so made that the outside line of the teeth is substantially parallel with the axis of the shells.

In order to expand the device and lock it 70 in position, I have shown a nut 6 threaded to fit the bolt, with its periphery fitted to slide upon the interior inclined surfaces 4. The inner end of the bolt 3 is guided and turnable in the hole 7 which is made in that 75 end of the shell; and the outer part of the bolt passes through the hole in the outer end of the shell. The head 8 of the bolt abuts against the outer end of the part to be secured, and when turned it will advance the, 80 nut 6 within the shell.

The device is assembled as follows: A hole of the proper diameter and depth having been made where the attachment is to be placed, the nut may be introduced into 85 the segments. The segments A—A may then be pushed to the bottom of the hole, or as far as may be desired. The nut 6 being at the inner end of the shell, will allow the segments to be closed sufficiently to enter the 90 hole, and the nut to lie in the channel between the surfaces 4. The bolt 3 may then be turned, and the nut caused to travel along the hollow interior of the shells so that the nut 6 will act against the convergent channels, and force the shells A—A 95 outwardly so that the teeth 5 upon the outside will engage with the interior of the opening in which the fixture is to be placed, and lock it firmly in place. 100

An important feature of this construction is that the outward pressure is always in the transverse plane of the nut, always keeping pace with the travel of the nut, and there will be no leverage tending to bend or distort the shells, as will be produced if the shells are united at one end, and an expander caused to travel within them. 105

As the points of the teeth 5 are substantially parallel with the interior surface of 110

the opening, it will be seen that they will be forced to engage evenly, and thus lock the shell for its whole length.

Any desired attachments may be made to 5 the projecting ends of the bolt 6 that are desired, and in case of any loosening of the parts, it is only necessary to give the bolt 3 a turn or two to again lock them firmly in place.

10 It will be seen that this construction enables me to use standard bolts and nuts obtainable in any hardware store, and that by reversing the bolt so that the hexagonal head is movable within the shell, the screw-threaded end of the bolt will project, and will serve to support any desired fixture after the device has been locked in place by turning up the nut.

Having thus described my invention, what 20 I claim and desire to secure by Letters Patent is—

1. In a locking attachment for walls and the like, a shell composed of two opposed members separated in a plane through the 25 axis of the complete shell, said shell having a hexagonal interior, the opposed surfaces of which approach each other from the rear toward the front and each of which surfaces has an equal width from end to end, 30 and the surfaces which meet the dividing line being convergent, a bolt guided and turnable longitudinally within the shell, a hexagonal nut upon said bolt, two opposed sides of which are adapted to travel upon 35 the equal interior and opposed surfaces of the shells whereby said shells are separated and caused to bind within an inclosing hole.

2. In a device of the character described, 40 a hollow shell composed of two segments having the edges meeting in a plane through the longitudinal axis of the shells, each segment having toothed exterior surfaces midway between the meeting edges, and having 45 a hexagonal interior, the two sides which correspond with the toothed surfaces inclining toward each other from the rear to the front and each of which sides is of equal width from end to end, and the sides which register with the meeting edges of the shells

being convergent from one end to the other, 50 a hexagonal nut fitting said shells having the sides of a length corresponding with the two straight interior sides whereby the nut may be moved from end to end without binding, said nut acting to separate the 55 shells and cause the exterior teeth to bind in a containing chamber, and a screw-threaded bolt passing through the nut and adapted when turned to draw the nut from the wider to the narrower end, and cause the 60 members of the shell to be separated.

3. In a device of the character described, 65 segmental hollow shells having the interior hexagonal with the sides which correspond with the meeting edges of the shells made tapering, and the opposing sides approaching each other from the rear to the front and having the edges parallel from end to end, a nut slidable and guided within the shells, a screw-threaded bolt extending axially through the nut and shells, and adapted to draw the nut outwardly and expand the shells, teeth formed upon the exterior of the shells corresponding with the straight 75 interior sides, said teeth having broad reinforcing bases convergent to their points, and adapted to engage the interior of the chamber in which the shells are fitted.

4. An anchor lock including half shells 80 with opposed serrated projections upon the backs of said shells, longitudinal interior channels, the bottoms of which have parallel edges and correspond in position with the exterior teeth, said shells being gradually thickened from one end to the other 85 to correspondingly decrease the depth of the channel, a nut, two opposed sides of which fit and travel upon the inclined bottoms, and a threaded screw passing through the nut and turnable to advance the nut and 90 separate the shell sections.

In testimony whereof I have hereunto set my hand in presence of two subscribing witnesses.

LOTHAR R. ZIFFERER.
